GEORGE WILLIS DUNHAM, OF. UTICA, NEW YORK, ASSIGNOR TO WHIRLDY CORPORATION, OF UTICA, NEW YORK, A CORPORATION OF NEW YORK

LAUNDRY MACHINE

Application filed March 25, 1925. Serial No. 18,086.

This invention relates particularly to laundry machines for domestic use.

Some of the more important objects of the invention are to provide an efficient form of clothes washer, in which both the lighter and the heavier dirt will be removed and kept separated from the clothes during the washing operation; to enable the rinsing and drying operations being effected in the same machine without shifting or disturbing the clothes container or other relatively heavy parts of the washing mechanism; to provide an effective circulation of washing fluid, free of stuffing boxes or other possible points of leakage; to protect the necessary gearing and insure proper lubrication of the same; to reduce friction and enable the employment of a relatively light economical motor; to provide convenient, handy control mechanism and in general, to provide a machine which will be entirely practical and efficient for the purposes intended.

These and other objects are attained by certain novel features of construction, combinations and relations of parts as herein-after disclosed and broadly claimed.

The drawings accompanying and forming part of this specification illustrate a typical and at present, preferred embodiment of the invention, but it should be understood and will be apparent from the scope of the disclosure and claims, that the structure may be modified and changed in various respects without departure from the spirit and scope of the invention.

Figure 1 in the drawings is a side elevation and part sectional view of the complete machine.

Figure 2 is an enlarged, broken and part sectional view of the gearing, pump, central column and control portions of the machine.

Figure 3 is a broken top plan, and

Figure 4 is a bottom plan view of the machine.

Figures 5 and 6 are enlarged horizontal and vertical sectional views respectively of the gearing, the first taken as on the plane of line 5—5 of Figure 6 and the second as on the plane of line 6—6 of Figure 5.

Figure 7 is a broken part sectional view

of the centrifugal clutch pulley as taken on substantially the plane of line 7—7 of Figure 5.

Figure 8 is a vertical sectional detail of the valved connection between the riser and tank.

The clothes container is shown as consisting of a receptacle 10 having an upwardly flaring side wall and a bottom which inclines downwardly from the rim, as at 11, and thence upwardly as at 12 to a central tubular portion 13 having a cap or shoulder 14 at the top resting on an anti-friction bearing 15, carried by a tubular post 16. This post rises from the bottom of an enclosing tank 17 and is shown in Figure 2 as set into a hub or collar 18 projecting from a base plate 19, bolted over a central opening 20 in the bottom of the tank.

The receptacle 10 is intended to hold both the clothes and the washing, rinsing, bluing or other treating liquid and for that reason is shown as imperforate, except for a series of overflow openings 21 provided in the upper portion of the side wall in the plane of greatest diameter. Above such openings, an upwardly inclined guard flange 22 is shown extended inwardly a sufficient distance to prevent escape of the clothes and illustrated as having a curled or rolled edge 23 to prevent tearing or injury to the clothes or other articles. The upwardly coned bottom portion of the receptacle is shown as braced and reinforced by a wide flange or disc 24 secured at the inside to the base of the sleeve 13 and at the outside to the deepest portion of the bottom.

The bearing cap is shown as contracted or reduced above the shoulder 14 to form a sleeve 25 provided at its upper end with key ways 26 to receive the external keys 27 on the lower end of the sliding clutch collar 28. This collar has a set of internal keys 29 engaged with corresponding key ways 30 on a tubular drive shaft 31 which extends up through 32 and has a bearing 33 in the upper end of the supporting column 16.

The clutch collar 28 is shown as provided with an annular hand hold 34 at its upper end by which it may be raised and lowered to 100

couple and uncouple the driving shaft and clothes receptacle. In Figure 2 this collar is indicated in two positions, being shown at the left lowered to uncouple the teeth or keys 27, 26, and at the right, as raised to bring these teeth into engagement and hence couple the driving shaft to the receptacle. To prevent accidental shifting of the movable clutch element, the same may be yieldingly held in either position as by means of a spring 20 pressed retainer 34.

In the present disclosure, an agitation of the clothes is effected during the washing operations by an agitator consisting of a conical support 35 carrying a series of dependent blades 36 having the lower or rubbing edges of the same inclined downwardly and outwardly as shown at 37. A partial rotary or oscillatory motion is imparted to this agitator or rubber by a drive shaft 38 extending up through the hollow shaft 31 and shown formed with key ways 39 at its upper end to receive the corresponding keys 40 on the sleeve 41 which forms the hub or central support of the rubber. This sleeve is shown as closed over the top of the shaft so as to form a cover over the clutch collar and other parts and is indicated as having an annular grip 42 forming a handle by which the agitator may be readily lifted off the end of the shaft and be removed from the machine.

The enlarged or domed portion 43 of the agitator sleeve which covers the clothes receptacle clutch also serves as a guard covering the clutch collar and so preventing accidental operation of the clothes receptacle clutch so long as the agitator is in operation. This is a safety feature, making it necessary to remove or disconnect the clothes agitator before spinning the receptacle for centrifugal drying operations.

To permit the rubbing blades to adapt themselves more or less to the clothes being washed, the support which carries said blades is shown as having a vertically sliding keyed engagement 44 on its supporting sleeve or hub, enabling the rubber proper to rise and fall with inequalities in the wash, preventing tearing of the clothes and insuring more effective and complete washing of the clothes. The necessary gearing for oscillating the agitator shaft and for rotating the high speed clothes container driving shaft is all contained in an oil-tight casing 45 in the present illustration, so that proper lubrication of these parts is assured without special attention on the part of the operator.

The agitator shaft is shown as journaled in a step bearing 46 in the bottom of the gear case and as carrying a pinion 47 engaged by a rack 48 pivoted on the bottom of the casing at 49 and operated by a link 50 pivoted thereto at one end at 51 and pivoted at its opposite end at 52 to a worm gear 53 engaged by the worm 54 on the drive shaft 55.

The high speed shaft is shown as having a bearing on the pinion 47 of the agitator shaft and as operated by a worm gear 56 in mesh with a worm 57 on the drive shaft. The gears disclosed are arranged and proportioned to effect the required relatively slow oscillation of the rubbers and a comparatively rapid rotation of the clothes container.

The power for operating the machine is shown as an electric motor 58 suitably supported on the bottom of the tank provided with a pulley 59 carrying a belt 60 running over a pulley 61 on the main gear shaft.

To enable use of a relatively small, light and inexpensive motor and particularly one adapted to alternating current operation, an automatic clutch is interposed in the present disclosure in the motor connections for automatically picking up the load after the motor has passed the critical point in starting and is capable of carrying the load. This clutch, as shown particularly in Figures 5 and 7, consists of a series of centrifugally acting clutch elements 62 sliding in radial guides 63 in the web of the pulley 61 and engaging an overstanding clutch drum 64 carried by a collar 65 fixed on the gear shaft 55 by a key 66. The pulley 61 is journaled on the collar 65, being rotatably confined thereto by the flange 67. In starting therefore, the first effect of the motor is simply to spin the clutch pulley 61. The clutch segments are suitably weighted so that they will be thrown outwardly into frictional engagement with the surrounding clutch drum and take hold gradually, but only after the motor has acquired sufficient speed and power to start the load. This clutch is also a safety factor in that if anything should go wrong, the clutch will slip and prevent injury to the parts.

Circulation and transfer of the washing or other fluid are provided for in the machine illustrated by a pump shown as consisting of an impeller 68 concentric with the vertical shafting described and carried by a tubular shaft 69 surrounding the high speed shaft 31, said impeller operating in a pump casing interposed between the bottom of the tank and the gear case, the upper half 70 of such casing being formed as a part of the base 19 and the lower half 71 being secured directly to the top of the gear case and forming a partition between the gear case and pump. The inlet to the pump casing is by way of openings 72 to the bottom of the tank and the outlet from the pump consists of a conduit 73 extending underneath the bottom and up the side of the tank in the nature of a riser. The discharge from this riser is shown as a down-turned nozzle 74 having a vertical portion 75 slidably and rotatably fitted in the riser and slotted for a portion of its length at 76, as shown in Figures 1 and 8, to serve as a valve for the passage 77 which opens outwardly from the tank into the side of the riser.

It will be clear from the views referred to that when the nozzle is raised to bring the valve slot 76 into register with passage 77, the pump will discharge directly back into the tank, the rate of such discharge being governed by the amount of valve opening. With the nozzle lowered to entirely close off this valve, the entire discharge of the pump will be through the nozzle, which may be turned to direct such discharge into the clothes container, into the top of the tank or out of and away from the tank.

A special feature of the pump is the elimination of objectionable stuffing boxes or packing glands by a water retaining construction consisting of a pipe 78 set into a hub 79 in the bottom of the pump casing and extending up above the highest liquid level that will be normally used in the tank. This protective piping extends up inside the hollow pump shaft 69 and the hollow pump shaft is connected with the high speed shaft over the top of such piping by a drive collar 80 shown as having a set screw connection 81 with shaft 31. The pump is thus driven by the high speed shaft and the possibility of any leakage is overcome in a frictionless manner by interposition of the stand pipe 78 which forms a water excluding well about both the high speed and agitator shafts.

To protect the pump, a conical strainer 82 is shown having a relatively close fitting engagement at the top about the supporting column 16 and removably seated at its lower end in the central opening 20 in the tank bottom directly over the pump casing. In addition to protecting the pump, this strainer prevents any articles that might fall into the tank from being injured by being drawn into the pump.

In operating as a washer, the clothes are usually placed in the container 10 with a suitable quantity of washing liquid and with the clutch collar 28 in the lowered position and the agitator sleeve 40 engaged over the end of the central shaft 38, as indicated at the left in Figure 2, the agitator will be oscillated back and forth causing the inclined blades 36 to exert a rubbing and rolling action on the clothes. This rubbing action may be accompanied by a washing circulation by turning the nozzle 74 so as to direct all or a portion of the wash water into the clothes container, which water by overflowing the container carries off both the lighter dirt in the form of a scum and the heavier dirt released by the rubbers and which is prevented from settling in the container by the agitation and the flow of water. The overstanding guard flange 22 prevents the lighter articles being carried off by this circulation which escapes through the drain openings 21.

The lighter matter washed from the clothes floats on the surface of the liquid in the tank and so is not drawn off by the pump, and

while the heavier matter settles to the bottom, this is not taken off by the pump, being held back by the screen and by reason of the fact that the velocity at the pump inlet is relatively low because of the number and size of the inlet openings and the wide area from which the pump draws its supply. By lifting the nozzle, the valved passage 77 from the tank into the riser is opened and the pump may then be made to discharge all or a portion of the liquid in circulation directly back into the tank without sending it up through the nozzle. If it is desired to waste the water, the nozzle may be lifted far enough to clear the top of the tank and then turned outward to direct the stream clear of the tank, as indicated by the broken lines in Figure 1.

When the washing is completed, the agitator may be disconnected and removed by simply lifting it off the supporting shaft 38. If desired, rinse water or other liquid for bluing or otherwise treating the contents of the container may then be circulated by properly controlling the action of the pump. During these various operations the tank may be temporarily closed by a removable cover 83.

The clothes are dried without removing them from the container by coupling the container directly to the high speed shaft. The removal of the agitator uncovers the clutch collar 28 and then by lifting this collar as indicated at the right in Figure 2, a direct clutching engagement is effected by the interlocking teeth 26, 27 on the container and drive shaft 31 respectively. Upon starting the motor, the centrifugal clutch in the pulley 61 picks up the load gradually and the container is rotated at sufficient speed to discharge the liquid by centrifugal force through the drainage openings 21. During this centrifugal drying operation, escape of any of the articles is prevented by the overstanding guard flange 22.

The approximate liquid levels during the washing and the drying operations are indicated in Figure 1 by the lines 84 and 85, the tank being capable of holding all the liquid from the container plus the extra amount required for proper washing operations.

During the washing operations, the clothes container has a tendency to follow the oscillatory motions of the rubber. To overcome this effect a yielding bumper or stop may be provided as indicated in Figures 1 and 3, the same being shown as a T-shaped lever 86, pivoted inside the tank at 87, extending inwardly into position for engagement by a stud 88 projecting up from the rim of the container, said lever having springs 89 engaged beneath the arms forming the head of the same to enable the stop to yield in either direction. The stud 88 is shown pivoted at 90 so that it may be swung outwardly manually to clear the

stop when the container is to be rotated for drying purposes. If desired, said stud may be mounted so as to automatically swing outwardly under centrifugal action to the position shown by the dotted lines in Fig. 1.

5 As indicated in the drawing, the stud 88 normally remains in a vertical position. It will be understood that the weight of the stud may be so distributed that the comparatively 10 great force exerted thereon by rotation of the receptacle under centrifugal drying action causes the stud to fall over or fly outwardly to the position indicated by the dotted lines in Fig. 1. It will be understood that the comparatively 15 small force exerted on the stud 88 during the comparatively gentle oscillation of the receptacle back and forth, due to the washing action of the agitator under some conditions, is not sufficient to cause the stud to fall over to its dotted position.

20 To enable the apparatus being entirely drained, a valve or drain plug 91 may be located in the lowest part of the circulating system, the same being shown interposed in the discharge conduit 73 leading from the pump.

25 The arrangement of the supporting column, drive shafts and pump all in concentric relation, provides a balanced structure and enables these parts to be combined as a unit applied to a single opening in the center of the 30 tank. The stand pipe extending up from the gear case and surrounding the drive shafts provides a stationary frictionless seal, preventing any leakage of water about the shafts 35 or down into the gear case. The agitator is supported independently of the tub or clothes container so that the operation of one is independent of the other and any slight misalignment of parts has no disadvantageous 40 effect. The constant water circulation carries off the dirt as fast as it is released and the arrangement disclosed prevents the entry of such dirt back into circulation so that the washing water is kept as clean as possible.

45 The domed center of the agitator acts as a cap preventing accidental shifting of the high speed clutch and protecting the clutch and shafting from splash water. As the clothes container is supported on the stationary column entirely independently of the drive shaft, said shaft is subjected only to a driving function and is not affected by misalignment or unbalanced relations of the container. The centrifugal clutch automatically relieves 50 the mechanism of undue loads that might strain the parts and enables the use of a small motor by permitting it to develop the required torque before assuming the load. The combining of all the gearing in a small closed 55 case is an aid to simplicity and compactness. protects the gears and enables them to operate under best conditions, surrounded by lubricant. The pump is of simple design, is operated directly from the high speed shaft 60 and this shaft, stepped in a bath of oil, is

amply able to carry the thrust of the pump with the least friction and wear. The various controls for the machine are all located at the top and therefore within convenient reach of the operator.

70 The container for the clothes is a receptacle of the closed or imperforate type so far as the washing action is concerned since it is capable of holding the clothes and wash water. The pump, gear case and supporting column may be considered as a combination unit which can be handled and applied as such over the opening in the bottom of the tank. The bypass for throwing the discharge from the pump back into the tank is readily controlled by sliding and rotating the nozzle in the riser portion of the pump conduit. The drain cock located at the lowest portion of the pump conduit beneath the tank serves for draining both the pump and the vertical portion of the conduit.

75 The motor is governed by a suitable controller and the same is shown as a switch 92 located inside one of the hollow legs 93 supporting the tank and actuated by a rod 80 or link 94 extending up the side of the tank through a guide 95 and provided with a convenient hand-hold 96 located within easy reach near the top of the tank. The gearing being entirely enclosed and operating in oil, 85 performs quietly, efficiently and requires no special attention.

90 The structure illustrated involves a practical commercial embodiment of the invention, but changes from this disclosure may 100 be found desirable or necessary to meet particular requirements, such changes being contemplated and coming within the scope of the appended claims. It should be understood also that the language employed herein is used in a descriptive rather than in a 105 limiting sense, except possibly for such limitations as may be imposed by the prior art.

95 Some of the features such as the spring buffer for the clothes receptacle and the bypass between the riser and tank may be omitted under certain circumstances, as in different models of the machine.

110 The riser may be extended below the lateral portion of the pump conduit so as to form 115 a well or trap 97, for sediment or the like and the drain plug be located at the bottom of this well. The trapped sediment can thus be readily drained off. To reduce vibration and facilitate assemblage of the parts, the intermediate section of the pump conduit may consist of a section of rubber hose 98 engaged at the inner end over the mouth of the pump outlet and at the outer end over a lateral extension 99 on the side of the riser. 120 The riser thus constitutes a separate unit which may be secured at the side of the tank by suitable clamp brackets 100 and 101, the latter or upper one being shown constructed with upstanding walls to form a cup for 125 130

catching any leakage about the nozzle and draining the same back into the tank through an opening 103 in the tank wall.

The nozzle may be further utilized to control the circulation by extending the vertical portion of the same down into the trap and providing it with a valve opening 104 for registry with the lateral extension 99. The lower end of the nozzle is shown as bearing on the bottom of the trap so as to definitely position the valve opening in the plane of registry with the pump passage.

It will be seen that upon lifting the nozzle the pump passage may be closed off and to prevent the nozzle being accidentally lifted past this closed position, an inwardly projecting stop 105 is shown on the upper portion of the nozzle for engagement with the overstanding rim 106 of the tank. A direct lifting movement of the nozzle to the extent permitted by this stop therefore serves to shut off the pump discharge. Upon turning the nozzle outwardly, however, the stop will be carried from beneath the limiting flange and the nozzle may then be lifted far enough to bring the lower end of the nozzle pipe into register with the lateral passage 99; whereupon, the discharge will be through the nozzle, controlled by the lifting, lowering and turning movements of the nozzle. In this elevated position the nozzle will be high enough to discharge into a stationary tub, sink or the like.

In the foregoing description and in the claims the term imperforate type as applied to the receptacle is intended to include any type of receptacle which is sufficiently imperforate to hold laundry liquid for washing regardless of the fact that holes may be provided for certain purposes.

What is claimed is:

1. In apparatus of the character disclosed, a tank, a tubular column therein, a clothes receptacle journaled on said column, a drive shaft for the receptacle extending up through said column, a clutch for coupling and uncoupling said shaft to and from the receptacle, an agitator shaft extending up through said drive shaft, an agitator operating in the receptacle, means for coupling and uncoupling the agitator with respect to the agitator shaft, a gear box at the foot of the column and gearing in said box for operating the drive shaft and agitator shaft respectively.

2. In apparatus of the character disclosed, a tank having a bottom opening, a pump casing and gear box secured over said bottom opening, a supporting column extending from the pump casing up through the opening into the tank, shafting extending from the gear box up through said column, a clothes receptacle journaled on the column and adapted to be driven by a portion of the shafting, agitator mechanism adapted to be

driven by another portion of the shafting, gearing in the gear box for operating the shafting and an impeller in the pump casing connected with the shafting, said pump having communication with said tank.

3. In apparatus of the character disclosed, a tank, a supporting column in said tank, a clothes receptacle journaled on said column, a drive shaft for said receptacle extending up through the column, a water retaining tube extending up into the column around the drive shaft, a pump at the foot of the column, including an impeller and a drive shaft for the impeller connected to and extending from the receptacle drive shaft down over the water retaining tube, said pump having communication with said tank.

4. In apparatus of the character disclosed, a tank, a clothes receptacle operating in the tank, a pump including a casing in communication with the tank and an impeller operating in said casing, a gear case below the pump casing, a drive shaft for the clothes receptacle extending from the gear case up through the pump casing and inside the impeller, a water retaining tube extending from the gear case up over said drive shaft and a drive shaft for the impeller connected with the receptacle drive shaft over the top of the water retaining tube.

5. In apparatus of the character disclosed, a tank, a clothes receptacle operating in the tank, a pump including a casing in communication with the tank and an impeller operating in said casing, a gear case below the pump casing, a drive shaft for the clothes receptacle extending from the gear case up through the pump casing and inside the impeller, a water retaining tube extending from the gear case up over said drive shaft, a drive shaft for the impeller connected with the receptacle drive shaft over the top of the water retaining tube, an agitator shaft extending from the gear case up through the receptacle drive shaft and an agitator within the receptacle adapted to be driven by said agitator shaft.

6. In washing and drying apparatus, a tank, a pump casing secured to the bottom of the tank, a tubular column extending from said pump casing up into the tank, a gear case below the pump casing, a water retaining tube extending from said gear case through the pump casing up into the column, a clothes receptacle journaled on the column, a drive shaft for said receptacle extending from the gear case up through the water retaining tube, an impeller within the pump casing and a drive connection for said impeller being connected to and extending from the drive shaft down over the outside of the water retaining tube, said pump having communication with said tank.

7. In apparatus of the character disclosed, a tank having a bottom opening and a combination unit applied over said opening com-

prising a pump casing open to the tank and carrying a column projecting up into the tank, a gear case below the pump casing, gearing in said case and shafting extending from 5 said gearing up through the pump casing and the column supported thereby.

8. In apparatus of the character disclosed, a tank having a bottom opening and a combination unit applied over said opening comprising 10 a pump casing open to the tank and carrying a column projecting up into the tank, a gear case below the pump casing, gearing in said case, shafting extending from said gearing up through the pump casing 15 and the column supported thereby and a water retaining tube extending from the gear case up around said shafting.

9. In apparatus of the character disclosed, a tank having a bottom opening and a combination unit applied over said opening comprising 20 a pump casing open to the tank and carrying a column projecting up into the tank, a gear case below the pump casing, gearing in said case, shafting extending from 25 said gearing up through the pump casing and the column supported thereby, a water retaining tube extending from the gear case up around said shafting, a clothes receptacle journaled on the column and clutch means at 30 the top of the column for coupling and uncoupling the receptacle and drive shaft.

10. In apparatus of the character disclosed, a gear case, gearing enclosed in said case, shafting operated by said gearing and 35 projecting upwardly from the case, a pump casing over the gear case and having an inlet opening, a supporting column projecting from the pump casing around the shafting, a water retaining tube surrounding the shaft- 40 ing, an impeller in the pump casing and a tubular connection for driving the same connected to and extending from the drive shafting down over the water retaining tube.

11. In apparatus of the character disclosed, 45 a clothes receptacle, a surrounding tank, a receptacle operating shaft extending up through the bottom of the tank, a water circulating pump concentrically disposed with respect to said shaft, a water retaining 50 tube surrounding said shaft and a tubular pump operating connection connected to and extending from said shaft down over the water tube.

12. In apparatus of the character disclosed, 55 a tank, a clothes receptacle journaled in the tank, a shaft for rotating the receptacle, a pump in communication with the tank and arranged concentrically with respect to said shaft and a conduit from the 60 pump said conduit having means controllable to direct the discharge of the pump into the tank or the receptacle, and structural devices for maintaining the discharge end of said conduit in operative relation to said selected 65 positions.

13. In apparatus of the character disclosed, a tank, a supporting column in said tank, a clothes receptacle journaled on said column and having a clutch sleeve at the top of the same, a drive shaft extending through 70 said clutch sleeve, a clutch collar slidably interposed between said shaft and sleeve for coupling and uncoupling the shaft and receptacle and an agitator having a hub portion covering said clutch collar. 75

14. In apparatus of the character disclosed, a tank, a supporting column in said tank, a clothes receptacle journaled on said column and having a clutch sleeve at the top of the same, a drive shaft extending through 80 said clutch sleeve, a clutch collar slidably interposed between said shaft and sleeve for coupling and uncoupling the shaft and receptacle, an agitator shaft extending up through the receptacle driving shaft and an 85 agitator removably engaged on said agitator shaft and covering the clutch collar.

15. In apparatus of the character disclosed, a tank, a clothes receptacle journaled therein, a pump, a conduit extending from 90 the pump and including a riser at the side of the tank, a nozzle slidably engaged in said riser for directing a discharge of the pump back into the receptacle and a bypass from the riser into the tank controlled by said 95 slideable nozzle.

16. In apparatus of the character disclosed, a tank having an opening in the bottom of the same, a pump casing secured over said opening and open to the tank, a column extending from said pump casing up into the tank and a conical strainer removably seated in the tank opening extending from the pump casing upwardly and inwardly to the column. 100

17. In washing apparatus, a rotatably supported clothes receptacle, a spring buffer engageable by said receptacle and yieldable in opposite directions to cushion and start the receptacle oscillating in opposite directions and an oscillating agitator operating on the contents of the receptacle and thereby tending to swing the receptacle oppositely into engagement with the buffer. 110

18. In washing apparatus, a rotatably supported clothes receptacle having a buffer element, a spring buffer engageable by said element and yieldable in opposite directions to cushion and start the receptacle oscillating in opposite directions, an oscillating agitator operating on the contents of the receptacle and thereby tending to swing said element oppositely into engagement with the buffer, means for rotating the receptacle to dry the contents by centrifugal force and means for automatically effecting disengagement of the element and buffer under such centrifugal drying action. 120

19. In apparatus of the character disclosed, a rotatably mounted clothes recepta- 125

- cle, a spring buffer for cushioning rotative movements of said receptacle and a pivoted stop on the receptacle adapted to be swung into position for engagement with or clear of the buffer. 5
20. In washing apparatus, a tank, a clothes receptacle journaled in said tank, drive gearing for the receptacle on the bottom of the tank, a motor for operating said gearing, legs 10 for supporting the tank, a switch for the motor mounted in one of said supporting legs and an operating rod for said switch extending from said leg up the side of the tank. 15
21. In washing apparatus, a tank, hollow legs supporting said tank, a motor for the washing apparatus mounted on the bottom of the tank, a controller for said motor mounted in one of the hollow legs of the tank and an operating rod extending from said controller up the outside to near the top of the tank. 20
22. In apparatus of the character disclosed, a tank, a clothes receptacle operating therein, a pump for circulating the washing fluid, 25 a conduit extending from the pump and including a riser at the side of the tank provided with a catch basin at the lower end of the same, a drain plug in said catch basin and a nozzle having an upright portion engaged in the riser and engaged in said catch basin. 30
23. In apparatus of the character disclosed, a tank, a clothes receptacle operating in said tank, a circulating conduit extending from the bottom of the tank, up the side of the tank and provided with a discharge nozzle at the upper end of the same and a drain from the upright portion of the conduit into the side of the tank. 35
- 40 24. In apparatus of the character disclosed, a tank, a clothes receptacle operating in said tank, a circulating conduit extending from the bottom of the tank, up the side of the tank and provided with a discharge nozzle at the upper end of the same and a drain from the upright portion of the conduit into the side of the tank. 45
- 50 25. In apparatus of the character disclosed, a tank, a clothes receptacle operating in said tank, a pump suspended from the bottom of the tank and subject to vibrations, a riser secured to the side of the tank and piping from said pump to the riser including a section of flexible tubing to prevent the vibrations of the pump from being communicated to said riser. 55
- 60 26. In apparatus of the character disclosed, a tank, a clothes receptacle operating in said tank, a pump on the bottom of the tank, a riser at the side of the tank, a lateral conduit from the pump opening into said riser, 65
- a nozzle shiftably engaged in the riser and having a portion for valving the lateral pump outlet and cooperating stops on the nozzle and tank for limiting the shifting movements of the nozzle, said stops being relatively disengageable upon a rotary turning movement of the nozzle with respect to the riser. 70
27. In apparatus of the character disclosed, a riser tube, a flow pipe adjustably disposed within said tube and means for securing said riser tube to a tank including a drainage cup for catching liquid leaking from the joint between said riser tube and flow pipe, whereby said drainage cup may drain into the tank. 75
28. In apparatus of the character disclosed, a tank, a riser tube at the side of said tank, a conduit connecting said tube and tank, a by-pass from said riser tube to said tank, a flow pipe having communication with said tank and with said tube, and means whereby said by-pass is controlled by movement of said flow pipe. 80
29. In apparatus of the character disclosed, a tank, a riser tube having a port spaced from an end thereof, a conduit connecting said port and tank, a flow pipe disposed within said riser tube and having a lower open end and an opening in its wall spaced from said end, whereby, when said opening and port are in register and also when the open end of said flow pipe is disposed above said port, communication is established through said riser tube and flow pipe. 85
30. In apparatus of the character disclosed, a receptacle having a clutch sleeve, a support for said receptacle, a drive shaft within said clutch sleeve, and a clutch collar slidably interposed between said clutch sleeve and drive shaft for coupling and uncoupling said shaft and receptacle. 90
31. In a laundry machine, a laundry receptacle having a clutch sleeve, a support for said receptacle, a tubular drive shaft within said clutch sleeve, a clutch collar slidably interposed between said clutch sleeve and drive shaft, means whereby, in the upper position of said collar, said receptacle and shaft are coupled and in the lower position of said collar said receptacle and shaft are uncoupled, an agitator, an agitator drive shaft within said tubular shaft, means whereby said agitator may be positioned on said agitator shaft only when said clutch collar is in its lower position. 100
32. In a laundry machine, a laundry receptacle, a support for said receptacle, an agitator, driving means for rotating said receptacle for centrifugal drying and operating said agitator for washing, said driving means including driving mechanism, a clutch for connecting and disconnecting said receptacle thereto and a drive shaft for said agitator, and means whereby said agitator may not be placed on said drive shaft when 105

said receptacle is connected to said driving mechanism.

33. In a washing apparatus, a rotatably supported laundry receptacle, a stop element, a spring buffer element engageable by said stop element and yieldable in opposite directions to cushion and start the receptacle oscillating in opposite directions, means for imparting an oscillatory motion to said receptacle, means for rotating the receptacle to dry the laundry by centrifugal force, and means for automatically effecting disengagement of the stop element and buffer element under such centrifugal drying action.

34. In apparatus of the character disclosed, a tank, a tubular supporting column rising from and supported by the bottom of said tank, a receptacle mounted on said column, a drive shaft for the receptacle extending up through the column, a pump having a rotary element concentrically disposed with respect to the shaft, at the foot of the column and drive connections from the shaft to said rotary element, said pump having communication with said tank.

35. In apparatus of the character disclosed, a tank, a tubular supporting column rising from the bottom of said tank, a receptacle mounted on said column, a drive shaft for the receptacle extending up through the column, a pump communicating with said tank and having a rotary element concentrically disposed with respect to the shaft, at the foot of the column and drive connections from the shaft to said rotary element, including a section of tubular shafting connected with the drive shaft at a point above the bottom of the tank and a tubular water well extending from the pump upwardly about the drive shaft and inside the tubular pump shafting.

36. In apparatus of the character disclosed, a tank having an opening in the bottom of the same and a drive shaft extending up through said opening, a pump having a rotary element and disposed below the tank and concentrically arranged with respect to said drive shaft, a water well extending from the pump up around the drive shaft and a tubular pump shaft extending from the drive shaft over the upper edge of the water well down to and connected with the rotary element of the pump, said pump communicating with said tank.

37. In apparatus of the character disclosed, a horizontally disposed rotary pump, a drive shaft extending freely up through the rotary element of the pump, a tubular water well extending from the bottom of the pump casing up around said shaft and a tubular shaft connected with the rotary element of the pump, extending upwardly around the water well and connected with the drive shaft over the top of the water well.

38. In apparatus of the character disclosed,

a horizontally disposed rotary pump, a drive shaft extending freely up through the rotary element of the pump, a tubular water well extending from the bottom of the pump casing up around said shaft and a tubular shaft connected with the rotary element of the pump, extending upwardly around the water well and connected with the drive shaft over the top of the water well, the pump casing consisting of horizontally separable sections, the upper section having a hub for supporting a tubular element surrounding the pump shaft and the lower section having a hub providing a seat for the tubular water well.

39. In apparatus of the character disclosed, a tank having a bottom opening, a rotary pump beneath the tank and in communication therewith through said bottom opening, said pump having a laterally extending discharge conduit and a riser extending from said discharge conduit into communication with the interior of the tank, said riser being rigidly secured to the side of the tank and the discharge conduit of the pump having a section of flexible hose interposed therein.

40. In apparatus of the character disclosed, a tank, a column rising from the bottom of said tank, a pump below the tank and connected therewith by a passage about the column and a substantially conical screen extending between the column and the bottom of the tank over said passage.

41. In apparatus of the character disclosed, a tank having a bottom opening, a rotary pump having a horizontally disposed casing suspended from the tank bottom and in communication with said bottom opening, a supporting column extending from the pump casing up into the tank, a receptacle mounted on said column, an impeller within the pump casing at the foot of said column, a gear box supported from the pump casing, a drive shaft for the receptacle extending from the gear box up through the impeller and the supporting column and connections from the drive shaft to the impeller.

42. In apparatus of the character disclosed, a tank having a bottom opening, a rotary pump having a horizontally disposed casing suspended from the tank bottom and in communication with said bottom opening, a supporting column extending from the pump casing up into the tank, a receptacle mounted on said column, an impeller within the pump casing at the foot of said column, a gear box supported from the pump casing, a drive shaft for the receptacle extending from the gear box up through the impeller and the supporting column and connections from the drive shaft to the impeller, including a tubular shaft secured to the drive shaft at a point within the column and extended downward to and connected with the impeller and a tubular water well extending from the pump

casing up inside the tubular pump shaft and about the drive shaft.

43. In apparatus of the character disclosed a rotary pump comprising a casing having an impeller therein, a drive shaft passing through the walls of said casing, the upper wall of said casing having an inlet opening, a tubular liquid retaining well secured to the lower wall of the casing, surrounding said shaft and extending up beyond said upper wall, and a drive member connected to said shaft above said well and to said impeller.

44. In apparatus of the character disclosed, a horizontally disposed rotary pump comprising a casing made up of separable sections, an impeller therein, a drive-shaft passing through the walls of both sections, the upper section having a tubular upstanding hub surrounding the drive-shaft and inlet openings arranged around said hub, the lower section having a depending hub surrounding said shaft, a tubular well seated in said depending hub and extending up beyond said upper section, and a drive sleeve connected to said shaft above said well and to said impeller.

45. In combination, a clothes receptacle rotatable on a vertical axis, a vertical shaft for driving said receptacle, a rotary pump concentrically disposed with respect to said shaft, means connecting the pump and shaft, a gear box dependent from and supported by said pump, means for supporting said pump, means in said gear box for driving said vertical shaft, and means for transferring liquid between receptacle and pump.

46. A laundry machine comprising a tank having a conical bottom plate sloping downwardly toward an opening in the center thereof, and a surrounding wall secured to said bottom plate at the edge thereof, a laundry machine assembly supported by said bottom plate at said opening, said assembly comprising a pump secured to the lower side of said bottom plate, a pedestal rising from said pump, a receptacle supported by said pedestal, and a gear box depending from said pump.

In testimony whereof I have hereunto set my hand.

50 GEORGE WILLIS DUNHAM.
